G. E. WILKINSON

DEVICE FOR LAPPING GAUGES

Filed May 26, 1919.

UNITED STATES PATENT OFFICE.

GEORGE ED. WILKINSON, OF ELGIN, ILLINOIS, ASSIGNOR TO ELGIN NATIONAL WATCH COMPANY, OF CHICAGO, ILLINOIS, A CORPORATION OF ILLINOIS.

DEVICE FOR LAPPING GAUGES.

Application filed May 26, 1919. Serial No. 299,743.

To all whom it may concern:

Be it known that I, GEORGE E. WILKINSON, a citizen of the United States, residing at Elgin, in the county of Kane, State of Illinois, have invented certain new and useful Improvements in Devices for Lapping Gauges, of which the following is a description, reference being had to the accompanying drawing and to the figures of reference marked thereon.

This invention relates to a device for grinding the opposite faces of gauges which are required to be very accurate as to thickness, and as to the parallelism, flatness and smoothness of their opposite faces.

The object of the present invention is to provide a simple, compactly arranged mechanism adapted to be attached to a lathe chuck or other rotating means which will 20 grind the opposite faces of gauge blocks to a required dimension, producing smooth, flat, parallel faces.

In the accompanying drawings, which show by way of illustration one embodiment 25 of the invention:—

Figure 1 is a sectional view of the device, showing the splined driving connection between the two lapping members and the manner of holding the work;

Fig. 2 is a plan view of the work holding means with its connections for producing an oscillating motion thereof; and

Fig. 3 is a view in elevation and plan of one of the gauges.

The device consists of a lapping member adapted to be rotated by a lathe chuck and provided with a centrally projecting post on which is splined an opposed lapping member. This splined connection includes a 35 spring for constantly forcing the lapping members together as they rotate. Between the flat opposed faces of these members and spaced therefrom, there is arranged a work holder adapted to hold a number of gauge blocks in position to be ground. The work holder is given an oscillatory motion relative to the grinders either by hand or by appropriate mechanism.

Referring more particularly to the drawings, the lathe chuck or other rotatable means 1 is adapted to receive the lapping member 2 provided with the central post 3 preferably threaded thereto at its inner end. Adapted to be rotated by the first lapping

member 2 is an opposing lapping member 4 provided with a central bore 5 through which said post 3 passes. Projecting through the side of this opposing lapping member 4 is a pin 6 the end of which takes in a groove 7 cut in a central boss 8 of the post 3. By means of this splined connection, the lapping members 2 and 4 are rotated together while permitting a relative movement toward and from each other.

To produce this movement, there is seated in the central bore 5 of the opposing lapping member 4 and surrounding the post 3 therein a coiled spring 9, one end of which presses against a steel washer 10 seated in the bottom of the central bore. To provide this seat, the inner wall of the bore 5 projects inwardly, as at 11. The other end of the spring 9 takes against a spool-like block 12 surrounding the upper portion of said post 3. This spool 12 is provided with upper and lower flanges 13 and a central annular channel 14 for the reception of a pin 15 threading through the side of the opposing lapping member 4 whereby said spring 9 is housed within said bore and is prevented from 80 springing out when the device is disassembled. Threaded to the projecting extremity of the post 3 is the spring adjusting nut 16 which in turn receives a locking screw 17 through its open bore. When the end of 85 this screw 17 is threaded into contact with the end of the post 3, the nut 16 is locked in position.

The gauges 18 to be ground are held between the two lapping members 2 and 4 by 90 means of any convenient work holding device herein shown as a flat plate ring 19 provided with a concentric raceway 20 for the reception of the gauge blocks 18. The central portion 21 of the ring is provided with 95 a bore through which freely passes the rotary post 3. Arranged on each side of the flat sides of this ring 19 are spacing plates 22 and 23, preferably located in recesses 24 and 25 in the opposing faces of the lapping members. By means of this construction the work holding ring is not only held in exact parallelism with the faces of the lapping members, but is suitably spaced therefrom so as not to be ground thereby.

The work holding ring may be either oscillated by hand or may be moved in relation to the lapping members by mechanical

means. In the present device the ring 19 is given a compound oscillatory movement, being provided for this purpose with two ears 26 and 27 connected to levers 28 and 29 which are caused to reciprocate by the cams 30 and 31 revolving independently of each other at such speeds as are found best by experience.

In operation, by unscrewing the nuts 16 and 17 from the post 3 the opposing lapping member 4 is free to be withdrawn from the lapping member 2 so that the gauge blocks can be inserted in the raceway 20 of the work holder 19. The parts are then reassembled and rotation imparted to the grinding members while, at the same time, the work holder is oscillated by its connection with the cams. As the gauges are reduced in thickness, the pressure of the spring 9 forces the second lapping member 4 toward the first. At fixed intervals the gauges are removed and transposed to other locations in the ring, to insure a uniformity in grinding.

Having thus described the invention, what I claim as new and desire to secure by Letters-Patent is:

1. In a device of the class described, the combination of a rotating lapping member, a second lapping member spaced therefrom and positively rotated thereby, work holding means normally arranged between said lapping members means for moving said work holder relatively to said lapping members, and means for moving one of the lapping members toward the other as the gauges in the work holding means are reduced in thickness.

2. In a device of the character described, the combination of a lapping member adapted to be attached to a lathe chuck to be rotated thereby, a second lapping member spaced from said first lapping member, and positively driven thereby, work holding means normally permanently located between said lapping members, spacing members between said work holding means and said lapping members to keep the faces of said lapping members in parallelism, and means for moving one of said lapping mem-

bers toward the other as the work is reduced in thickness.

3. In a device of the character described, the combination of a lapping member adapted to be attached to a lathe chuck to be rotated thereby, a second lapping member spaced from, but directly connected to said first lapping member to be positively driven thereby, work holding means normally concentrically located between said lapping members, spacing members between said work holding means and said lapping members to keep the faces of said lapping members in parallelism, means for moving one of said lapping members toward the other as the work is reduced in thickness, and means for moving said work holder laterally during the lapping operation.

4. In a device of the character described, the combination of spaced lapping members concentrically arranged and positively interconnected, means for rotating one of said members, concentrically arranged spacing members between said lapping members and the work holder to keep said lapping faces in parallelism, means for moving one of said lapping members toward the other as the work is reduced in thickness, and means for moving the work holder laterally of and during the rotation of the lapping members.

5. In a device of the character described, the combination of a rotating lapping member provided with a centrally arranged post, a centrally bored lapping member spaced from said first lapping member and splined to said post for rotation thereby, work holding means arranged between said lapping members and adapted to be moved relatively thereto, a spring arranged in said bore surrounding said post and adapted to press said second lapping member toward the first lapping member, and means for adjusting the tension of said spring.

In testimony whereof, I affix my signature in the presence of two witnesses.

GEORGE ED. WILKINSON.
